BUNK BED

James R. Jennings, 5833 Lawton Ave.,
Oakland, Calif. 94618

Filed Feb. 3, 1972, Ser. No. 223,404

Term of patent 7 years

Int. Cl. D6—01

U.S. Cl. D6—79

FIG_1

FIG_6

FIG. 1 is a front perspective view of a bunk bed showing my new design;

FIG. 2 is a top plan view thereof;

FIG. 3 is a front elevational view thereof;

FIG. 4 is a left side elevational view, the right side being substantially a mirror image thereof;

FIG. 5 is a rear elevational view thereof; and

FIG. 6 is a bottom plan view thereof.

I claim:

The ornamental design for a bunk bed, substantially as shown and described.
